[57] CLAIM

The ornamental design of a combination bicycle and waist pack, as shown and described.

DESCRIPTION

FIG. 1 is a front elevational view of a combination bicycle and waist pack showing my new design, the bicycle attachment straps being in an extended position; FIG. 2 is a rear elevational view thereof, the waist-encircling strap in its stored position;

FIG. 3 is a top plan view thereof;

FIG. 4 is a right side elevational view, the left side being a mirror image thereof;

FIG. 5 is a bottom plan view thereof;

FIG. 6 is a perspective view formed for attachment to a rear wheel bicycle rack; and,

FIG. 7 is a front elevational view with both bicycle and waist-encircling straps in their extended position.

FIG. 2.

FIG. 1.

FIG. 6.

FIG. 7.

FIG. 4.
